UNITED STATES PATENT OFFICE.

JOHN J. RUDDICK, OF NEWTON, MASSACHUSETTS, ASSIGNOR TO UNITED STATES ELECTRIC SIGNAL COMPANY, OF BOSTON, MASSACHUSETTS, A CORPORATION OF MASSACHUSETTS.

TRACK-RELAY FOR BLOCK-SIGNAL SYSTEMS.

1,174,450.

Specification of Letters Patent.

Patented Mar. 7, 1916.

Application filed December 26, 1913. Serial No. 808,653.

To all whom it may concern:

Be it known that I, JOHN J. RUDDICK, a citizen of the United States, residing at Newton, county of Middlesex, State of Massachusetts, have invented an Improvement in Track-Relays for Block-Signal Systems, of which the following description, in connection with the accompanying drawing, is a specification, like characters on the drawing representing like parts.

This invention relates to block signal systems of that type wherein each block of the track is provided with two insulated rail sections, and a track relay is rendered operative when the car or train runs onto these insulated sections for setting or restoring the signal. In signal systems of this type it is usual to provide two insulated rail sections at each end of the block, one of which is connected to the signal-setting magnet of the track relay, and the other of which is connected to the signal-restoring magnet of the track relay, the construction being such that normally both magnets are deenergized or inactive, but as soon as a car runs onto either insulated rail section the corresponding magnet will be energized thereby to close the signaling circuit which it controls. Track relays of this type have heretofore been so constructed that when the car or train passes onto the first insulated rail section in entering a block, the magnet which is thus energized will operate to close the signal-setting circuit, thus setting the signal, the other insulated rail section being the one which is used for restoring the signal. With this arrangement the signal-setting insulated rail sections are so placed relative to the signal-restoring insulated rail section that in entering the block from either end the car will always pass onto the signal-setting insulated rail section first and then pass onto the signal-restoring insulated rail section, while in leaving the block the operation is the reverse, that is, the car or train will always pass onto the signal-restoring insulated rail section before it passes onto the signal-setting insulated rail section.

In order to prevent the signals from being restored when the car or train entering the block passes from the signal-setting insulated rail section onto the signal-restoring insulated rail section, it is customary to provide some non-interfering mechanism which

will render the signal-restoring magnet inoperative whenever it is actuated immediately subsequent to the signal-setting magnet of the track relay. It sometimes happens, however, that this non-interfering mechanism does not work accurately, in which case the above described arrangement of track relay would cause the signal to be restored again by a car or train entering the block when said car or train passed off from the signal-setting insulated rail section and onto the signal-restoring insulated rail section. Moreover, with the above-described construction if a car runs by a signal set against it and enters the block and then backs out of the block, the signal may be restored when in fact this should not be done because the block is already occupied by another car. The present invention aims to provide a novel form of track relay for block signal systems of this type which is so constructed that the signal will not be set until the car or train entering the block has passed over the first insulated rail section and onto the second insulated rail section and has cleared itself from the first section, and the signal will not be restored until the car in leaving the block has passed over the first rail section onto the second rail section and has completely cleared said first rail section. Furthermore, the construction is such that if a car entering the block runs over and off from the first insulated rail section onto the second thereby setting the signal and then comes to rest and subsequently backs out of the block, the passage of the car from said second insulated rail section onto the first will cause the signal to be restored.

In order to give a clear understanding of the invention I have illustrated in the drawings a selected embodiment thereof which will now be described, and the novel features of the invention will then be pointed out in the appended claims.

Figure 1 of the drawings shows a track relay embodying the invention; Figs. 2, 3 and 4 show different positions of the controlling member which will be more fully hereinafter described.

I have shown at 1 a portion of a track which may be either a steam railway track or an electric railway track, and one rail of which is shown as provided with two insulated rail sections 2 and 3.

It is assumed that the section of track illustrated in the drawing is at one end of the block in a block signal system, and that at the other end of the block there will also be two insulated rail sections corresponding to those shown in Fig. 1. I have not, however, deemed it necessary to illustrate the full length of the block as the general operation of the block signal system of this nature will be well understood by those skilled in the art.

Associated with each insulated rail section is a magnet of a track relay by which the signals of the block signal system are set and restored, these magnets being designated by 4 and 5 respectively. The magnets herein shown are differentially wound and are operated in a manner similar to that shown in my Patent 1029067 dated July 29, 1913. These magnets may be supplied with current from any suitable source of current supply and where the invention is applied to an electric railway the current for energizing the magnets will naturally be taken from the trolley wire or feed conductor 6, as shown in the drawings.

7 indicates a wire or circuit leading from the feed conductor to the magnet 4. This magnet is wound with the two windings 8 and 9 which are oppositely wound and are in series, the winding 9 being connected by a wire 10 with the ground, which may be conveniently done by connecting the wire 10 to the track 1. The magnet 5 is also provided with the two windings 11 and 12 which are connected in series but are oppositely wound, the winding 11 being connected by the wire 13 with the feed conductor 6, and the winding 12 being connected to the ground or track 1 through the wire 14. With this arrangement there will be current normally flowing through both magnets 4 and 5, but as each magnet has two opposite windings thereon it will be normally deenergized. The winding 8 of the magnet 4 is connected to the insulated rail section 2 by a wire or connection 15, and the winding 11 of the magnet 5 is similarly connected to the insulated rail section 3 by a wire or connection 16. Under normal conditions no current will flow in the connections 15, 16 because they lead to insulated rail sections 2 and 3, but whenever a car or train passes onto either insulated rail section, then a current will be established through the shunt circuit 15 or 16, as the case may be, thus cutting out one of the windings of the corresponding magnet and causing the magnet to be energized. A track relay having this differential winding is described and claimed in my aforesaid Patent 1069027.

The magnet 4 is provided with an armature 17 which is pivoted at 18 and has rigid therewith an arm 19 carrying a contact 20

adapted to bridge two contacts 22 in the signal-restoring circuit 23. Similarly, the magnet 5 has an armature 24 pivoted at 25 and has rigid therewith an arm 26 which carries a contact 27 adapted to bridge two contacts 28 in the normally-open signal-setting circuit 29. The signal-setting circuit 29 and signal-restoring circuit 23 may receive current from any suitable source of supply and are herein shown as being connected to the trolley wire or feed conductor 6 by a connection 30.

The important feature of my invention resides in providing a novel construction whereby assuming that the track relay herein illustrated is at the left-hand end of the block and a train is entering the block in the direction of the arrow *a*, the signal-restoring magnet 4 is prevented from being operated when the car passes onto the insulated rail section 2 and when the car has passed clear of said insulated rail section 2 and onto the insulated rail section 3 the magnet 5 will be operative to close the signal-setting circuit thereby to set the signals in the block. Further, if the car which has thus passed into the block to set the signals should come to rest before it clears the insulated rail section 3 and should then back out of the block across the insulated rail section 2, the passage of the car onto the insulated rail section 2 will cause the signal-restoring magnet 4 to be operative thereby to restore the signals. The mechanism herein shown whereby these results are accomplished comprises a controlling member 31 pivoted at 32 and provided with two arms or wings 33, 34, each provided in its periphery or edge with three notches 34, 35 and 36, the middle notch 35 on each wing having less depth than the notches 34, 36. Each armature 17, 24 has rigid therewith an arm which cooperates with the controlling member 31, said arms being designated 37 and 38, respectively. The controlling member 31 is yieldingly held in its central position by any suitable means which will permit it to swing in either direction. As herein shown, said controlling member has rigid therewith an arm 39 provided with a pin 40 in its end which is received between two centering levers 41 that are pivoted at 42 to a stand 43 and are yieldingly connected by a spring 44, the upper end 45 of the stand serving to limit the movement of the centering members toward each other. The arms 37, 38 will preferably carry rollers 46 at their lower ends which are adapted to engage in the notches of the controlling member.

Fig. 1 shows the parts in their normal position when both magnets 4 and 5 are inactive, and it will be noted that the rollers 46 stand just below the points 47 between the notches 34 and 35.

Assuming now that a car is entering the

block in the direction of the arrow *a* and passes onto the insulated rail section 2, the passage of the car onto said insulated rail section 2 will cause the magnet 4 to be energized and the attraction of the armature 17 of the magnet will swing the arm 37 toward the controlling member 31 and will raise the contact 20 toward the contacts 22. This movement of the armature carries the arm 37 toward the controlling member 31, and as the roller 46 is just below the point 47 the engagement of the roller with the inclined surface of the notch 35 will turn the controlling member 31 into the position shown in Fig. 2, the roller 46 entering the notch 35 to the bottom thereof. The depth of this notch is such as to bring the arms 37 and 19 to rest before the contact 20 engages the contacts 22. The dotted line 48 20 designates the position of the arm 19 and contact 20 corresponding to the position of the arm 37 shown in Fig. 2. Although the magnet 4 is energized when a car or train passes onto the insulated rail section 2, yet 25 said magnet is not operative to close the signal-restoring circuit because of the above-described operation of the controlling member 31. When the car passes onto the insulated rail section 3 the magnet 5 will be 30 energized and the arm 38 thereof will swing toward the controlling member. The relation of the notches in the two wings 33 and 34 of the controlling member is such that when the parts are in the position shown 35 in Fig. 2 the apex or point 47 of the wing 34 is just below the roller 46 of the arm 38, and as a result, when the magnet 5 is energized by the passage of a car onto the insulated rail section 3 the arm 38 will swing 40 against the inclined surface forming part of the notch 54 on the wing 34. However, so long as the car or train is on both insulated rail sections 2 and 3 both magnets are energized and the controlling member 31 will 45 have no movement, but as soon as the car or train clears the insulated rail section 2, then the magnet 4 becomes inactive again and the energized magnet 5 acting through the arm 38 serves to turn the controlling member 31 into the position shown in Fig. 50 3, the roller 46 moving to the bottom of the notch 54 in the wing 34. The notch 54 is sufficiently deep so as to allow the arms 38, 26 to have a sufficient movement to close the contact 27 onto the contacts 28, thereby closing 55 the signal-setting circuit 29 and causing the signals at each end of the block to be displayed.

When the car passes completely into the block and off from the insulated rail section 3, then the magnet 5 becomes deenergized and the spring 44 returns the controlling member to its normal position. It will thus be seen that it is necessary for the car 60 or train to traverse across the signal-restor-

ing insulated rail section 2 and onto the signal-setting insulated rail section 3 before the signal will be set, and that means are provided for preventing the signal-restoring mechanism from being operated when the 70 car is on the signal-restoring insulated rail section. Similarly when a car is leaving the block in the direction of the arrow *b*, the passage of the car onto the insulated rail section 3 will energize the signal-setting 75 magnet 5, but the controlling member 31 will operate to prevent said magnet from being operative to close the signal-setting circuit 29, while when the car clears the insulated rail section 3 and passes completely 80 onto the insulated rail section 2, then the signal-restoring magnet 4 will become operative to close the signal-restoring circuit 23, the controlling member 31 operating as 85 above described.

My invention is also so arranged that if a car entering the block passes over the insulated rail section 2 and completely onto the insulated rail section 3 thereby setting the signals and then comes to rest before clearing 90 the insulated rail sections and subsequently backs out of the block, the passage of the car off from the signal-setting insulated rail section 3 onto the signal-restoring insulated rail section 2 will cause the signal to be restored. This is accomplished as shown in Fig. 4, for when the car moving in the direction of the arrow *a* passes over the signal-restoring insulated rail section 2 onto the signal-setting insulated rail section 3, the 100 controlling member will be in the position shown in Fig. 3, and the contact 27 will close the contacts 28. At this time the point or apex 50 between the notches 35 and 36 on the wing 33 will be just above the roller 46 on the arm 37 and, therefore, if the car backs off from the signal-setting rail section 3 onto the signal-restoring rail section 2, the deenergizing of the magnet 5 and reenergizing of the magnet 4 will release the 105 arm 38 and cause the arm 37 to enter the deep notch 36, and as said notch is of a sufficient depth to permit the armature 17 to swing a sufficient distance to close the contact 20 onto the contacts 22, it follows that the 110 signal-restoring circuit will thus be closed thereby restoring the signal.

Having fully described my invention, what I claim as new and desire to secure by Letters Patent is:—

1. In a block signal system, the combination with two magnets, of means for energizing said magnets, a switch operated by each magnet, and means to lock each switch from being closed when its magnet is energized except when the other magnet has been energized immediately previously.
2. In a block signal system, the combination with two magnets, of means for energizing said magnets successively, a switch 125

operated by each magnet, and means to lock each switch from closing when its magnet is energized except when said magnet is energized immediately after the other magnet is energized.

3. In a block signal system, the combination with a track having two insulated rail sections arranged so that a car will pass over them successively in entering a block, of a magnet associated with each rail section, means to energize each magnet as a car passes over the corresponding insulated rail section, a contact member actuated by each magnet, a signal-setting circuit closed by the contact actuated by the magnet associated with the second insulated rail section, a signal-restoring circuit closed by the other contact, and means to lock said latter contact from closing its circuit when its magnet is energized except when the other magnet has been energized immediately previously.

4. In a block signal system, the combination with a normally-open signal-setting circuit and a normally-open signal-closing circuit, of a contact member for each circuit for closing the same, a magnet for actuating each contact, means to lock each contact

from closing its circuit when its magnet is energized except when the other magnet has been energized immediately previously.

5. In a block signal system, the combination with two magnets, of means for energizing said magnets, a switch operated by each magnet, means normally locking each switch from operation when its magnet is energized, and means operated by the immediate previous energizing of the other magnet to render said locking means inoperative.

6. In a block signal system, the combination with two magnets, of means to energize each magnet, a switch operated by each magnet, a controller normally locking each switch from operation when its magnet is energized but rendered inoperative as a lock when the other magnet has been energized immediately previously.

In testimony whereof, I have signed my name to this specification, in the presence of two subscribing witnesses.

JOHN J. RUDDICK.
